UNITED STATES PATENT OFFICE.

ROBERT E. BELKNAP, OF CHICAGO, ILLINOIS, ASSIGNOR TO ANCHOR COMPANY, OF CHICAGO, ILLINOIS, A CORPORATION OF ILLINOIS.

RAIL-ANCHOR.

1,250,947.

Specification of Letters Patent. Patented Dec. 25, 1917.

Original application filed June 23, 1913, Serial No. 775,172. Divided and this application filed February 17, 1917. Serial No. 149,259.

To all whom it may concern:

Be it known that I, ROBERT E. BELKNAP, a citizen of the United States, residing at Chicago, in the county of Cook and State 5 of Illinois, have invented new and useful Improvements in Rail-Anchors, of which the following is a specification.

This invention relates to rail anchors or anti-creepers for rails.

10 This application is a division of an application filed by me June 23, 1913, Serial No. 775,172, which resulted in Patent No. 1,228,171, dated May 29, 1917.

One of the objects of this invention is to 15 provide a simple and reliable anchor which may be readily applied to the rails.

Another object is to provide an improved rail anchor having simple, efficient and easily applied means for retaining it in position 20 on the rail.

Other objects and advantages of the invention will appear in the following description and claims.

In the drawing:

25 Figure 1 is an end view of one form of the rail anchor of my invention in place. Fig. 2 is a side elevation of the anchor of Fig. 1. Fig. 3 is an end view of another form of anchor embodying my invention. 30 Fig. 4 is one of the details of the anchor of Fig. 3. Fig. 5 is an end view of still another form of anchor in accordance with my invention. Fig. 6 is a section on the line 6—6 of Fig. 5.

35 The anchor comprises a pair of jaws adapted to engage the base flange of the rail and to increasingly grip the base when the anchor meets the resistance of a tie as the rail tends to creep. In order to retain the 40 jaws in gripping position and to prevent displacement by the jar of passing loads and retrograde movement of the rail, retaining means engaging an edge of the rail base to oppose any displacing movement are provided. In order to facilitate the application 45 of the device the retaining elements are adapted to be positioned in a direction transverse to the length of the rail.

Referring to the construction of Figs. 1 50 and 2, the rail A is shown resting upon a tie B, against which a portion of the anchor impinges to prevent the rail from creeping. The anchor is shown as provided with a downwardly extending foot or leg 19, which 55 will abut against the tie some distance be-

low the rail as shown in Fig. 2. The rail is gripped on one side between an upper jaw 20 and a lower jaw 23, the disposition of the jaws and the construction of the foot being such that the jaws are normally 60 biased to grip the rail base. When the rail starts to creep so that the leg 19 begins to be forced against the tie, the anchor is rocked or tilted in a substantially vertical plane and the jaws grip the base more firmly. The 65 anchor then being in effect secured to the rail and abutting a stationary tie acts to prevent the rail from creeping. In order to more positively hold the anchor in place, especially when the leg 19 is not against a 70 tie, and to provide for additional gripping action, a second jaw or clip 21 is made to embrace or overlie the opposite edge of the rail base. This supplemental retaining member or jaw has an opening fitting over 75 a square projection 19^a, extending from the anchor body in a direction transverse to the length of the rail as clearly indicated in Figs. 1 and 2. The retaining member or supplemental jaw is thus placed in position 80 by being applied to the body extension in a direction transverse to the length of the rail. This method of application is exceedingly simple and requires little space for its easy accomplishment. A pin 22 extending 85 through an opening in the projection 19^a serves to prevent the jaw 21 from being jarred loose and holds it to the rail.

In Fig. 3 is illustrated another form of anchor having a depending foot or leg 7 for 90 abutting the tie as previously described. The anchor is also provided with an upper jaw 8 and a lower jaw 10 for gripping the top and bottom respectively of the rail base. There is a member or projection 7^a extending 95 from the anchor body transversely to the length of the rail to a point beyond the base as shown in Fig. 3. The jaw 8 has an extension or is provided with a member 8^a which extends through an opening b in the 100 rail web. The projection 7^a extends through an opening in a rod 9 (shown in detail in Fig. 4) which is applied thereto transversely to the length of the rail whose upper end is passed through the same opening b in the 105 rail web as the extension 8^a. In order to hold these parts securely to the rail the extension 8^a is bent downwardly and the upper end of the rod 9 is split and bent outwardly, as shown in the figures. In order 110

to hold the rod 9 to the extension 7^a the extreme outer end of the latter is split and bent as shown.

In Figs. 5 and 6 are shown a modified construction wherein similar jaws are provided on each side of the web, the jaws when in place being interlocked beneath the rail base. As shown the body portion has two practically similar interlocking sections or extensions 12 arranged to slide upon each other in a direction transverse to the length of the rail when being applied to the rail and to be secured against displacement. Each section has an extension 13 forming a jaw and the right hand section of Fig. 5 has a horizontal extension 14 on which is formed a bearing surface or jaw 14^a. This extension which is a little more than a semi-circle in cross-section is adapted to fit in a horizontal socket formed in an extension 12^a of the left hand section. This latter section is also provided near its lower end with a T-shaped socket 12^b adapted to receive an extension 12^a of the right hand section of the anti-creep, such extension being also substantially T-shaped in cross-section as illustrated in Fig. 6. This extension is adapted to slide in said slot and in order that the parts may be held together when in home position with a sufficient force to prevent displacement, I provide such extension with a small projecting point 12^c adapted to engage a depression or cavity 12^d in the base of the slot.

What I claim is:

1. A rail anchor comprising a body having a pair of jaws to grip the rail base between them and a tie abutting portion adapted to cause the jaws to tilt in a substantially vertical plane to increasingly grip the base when the rail tends to creep, and a retaining member for engaging an edge of the rail and adapted to be positioned upon said body by application thereto transverse to the length of the rail.

2. An anti-creep for rails comprising a body made in two sections arranged to slide upon each other and having means for engagement against displacement, each section having an extension forming in connection with the body a jaw to receive the rail-base, said body being adapted to tilt to cause the jaws to grip the rail-base.

3. A rail anchor comprising a body having a pair of jaws to grip the rail base between them and a tie abutting portion adapted to cause the jaws to increasingly grip the base when the rail tends to creep, and a retaining member applied to said body in a direction transverse to the length of the rail and adapted to embrace one edge of the rail base to prevent lateral displacement of the body.

4. A rail anchor comprising a body having a tie abutting extension and a pair of jaws embracing one edge of the rail base and adapted to increasingly grip the base when the extension abuts a tie as the rail tends to creep, and a retaining jaw adapted to be associated with said body and embrace the opposite edge of the rail base by being applied transversely to the length of the rail.

5. A rail anchor comprising a body portion having a pair of jaws embracing one side of the base flange of a rail and normally biased to grip the top and bottom of the base flange, a member extending from the body beneath and transversely of the rail base, and means applied to said member in a direction transverse to the length of the rail for engaging the edge of the rail base opposite the jaws to hold the anchor in place.

6. A rail anchor comprising a pair of jaws adapted to embrace one edge of the base of a rail and when tilted in a vertical plane to increasingly grip the rail base to prevent creepage, a depending leg adapted to abut a tie to tilt the jaws as the rail tends to creep, an extension from the jaws projecting therefrom in a direction transverse to the length of the rail, and a retaining member adapted to be applied to said extension in a direction transverse to the length of the rail to embrace the opposite edge of the rail base to prevent displacement of the jaws.

7. A rail anchor comprising a pair of jaws adapted to embrace the base of a rail and when tilted to increasingly grip the base to prevent creepage, a depending leg adapted to abut a tie to tilt the jaws when the rail tends to creep, an extension projecting from the jaws in a direction transverse to the length of the rail, a retaining member adapted to be applied to said extension in a direction transverse to the length of the rail and to embrace an edge of the rail base to prevent displacement of the jaws, and means to lock said retaining member in place.

8. A rail anchor comprising a body having a pair of jaws adapted to grip the rail base between them and a tie abutting leg adapted to cause the jaws to increasingly grip the base when the rail tends to creep, and a retaining member adapted to be positioned upon said body by application thereto transverse to the length of the rail and engaging an edge of the rail to oppose the tendency of the jaws to spring laterally from the rail base when the leg engaging a tie places the jaws under pressure.

In witness whereof, I have hereunto subscribed my name.

ROBERT E. BELKNAP.
